UNITED STATES PATENT OFFICE.

JOSEPH AMON, OF NEW YORK, N. Y., ASSIGNOR TO THE CUTLER-HAMMER MFG. CO., OF MILWAUKEE, WISCONSIN, A CORPORATION OF WISCONSIN.

ELECTRIC TERMINAL.

Application filed May 9, 1921, Serial No. 463,151. Renewed March 23, 1925.

This invention relates to an electric terminal.

Such a terminal is particularly adapted for use in an electric heater having a tubular jacket, although it may be used for other purposes.

The electric terminal to which this invention particularly applies comprising, in general, a conducting plug which may be inserted in the end of the tubular jacket of an electric heater and rigidly fastened thereto, the resistor being connected with the terminal.

Among the objects of this invention is to provide an efficient and durable electric terminal which may be readily and economically manufactured.

Another object is to provide improved means for fastening an electric terminal to a support.

Another object is to provide improved means for rigidly fastening an electric terminal to the jacket of an electric heater.

Another object is to provide an electric terminal which will not become loose due to temperature changes.

Other objects and advantages will hereinafter appear.

The views in the accompanying drawings are as follows:

Figure 1 shows a terminal fastened to the tubular jacket of an electric heater.

Figure 2 shows a heater jacket and terminal ready for assembling.

Figure 3 is a longitudinal central section through the heater and terminal shown in Figure 1.

Figure 4 is a transverse section on line 4-4 of Figure 3.

Figure 5 is a transverse section on line 5-5 of Figure 3.

Figure 6 shows a modified form of bushing for fastening the terminal to the jacket.

Figures 1 to 5 will first be described.

A terminal 1, surrounded with insulation 2, over which is placed a bushing 3, is rigidly fastened to the tubular jacket 4 of an electric heater.

The terminal comprises in general an elongated tubular conductor arranged to receive the end of a helical resistor 5.

The insulation 2 may take the form of a sleeve of mica or other suitable material.

The bushing 3 may be made of copper or other ductile material.

A peripheral groove 6 in the bushing 3 reduces the contact surface with the heater jacket and enables the bushing to be compressed more readily when the jacket is contracted thereon.

Another and smaller peripheral groove 7 in the bushing 3 assists in fastening the terminal to the jacket and prevents the longitudinal movement of the terminal with respect to the jacket. Of course, other means may be employed for preventing movement of the terminal with respect to the jacket.

The resistor 5 connected with the terminal 1 is insulated from the jacket 4 by means of suitable insulating material such as, for example, granular magnesium-oxide.

The terminal with its insulating sleeve 2 and bushing 3 is inserted in the end of the jacket 4 which is then swaged or otherwise contracted crosswise to rigidly fasten the terminal to the jacket.

The bushing 3 being of softer material than the jacket 4 is more readily compressed and thus prevents the jacket or terminal from being damaged while the terminal is being fastened to the jacket.

When the jacket is contracted on the bushing, the circular flanges thereof are compressed and the external diameter of the bushing is reduced.

The jacket is forced over the edges of the flanges and into the groove, as shown in Figure 3, thus assisting in preventing longitudinal displacement of the terminal.

Figure 6 shows a bushing having a helical peripheral groove.

When the jacket is contracted on this bushing, the helical flange thereof is compressed thereby reducing the external diameter of the bushing. The jacket is forced over the edges of the helical flange and into the helical groove. Thus, the bushing and jacket are rigidly interlocked, thereby preventing both rotative and longitudinal movement of the bushing in the jacket.

Various other embodiments and adaptations of the invention contained herein may be made.

The invention claimed is:

1. A terminal for electric heaters and the like, having tubular jackets, comprising a hollow conducting plug adapted to receive a connector, insulation surrounding the plug, and a compressible bushing arranged to rigidly fasten the plug to the jacket, the rigid

fastening being effected by contraction of the jacket.

2. Means for rigidly fastening a plug terminal to the tubular jacket of an electric heater, comprising a metallic bushing contracted on the terminal and having a helical integral flange with which the jacket is interlocked by contraction of the jacket thereon, and means electrically separating the terminal and jacket.

3. An electric heating unit comprising a metal tubular jacket, powdered heat refractory insulating material within said jacket, a resistance conductor embedded in said insulating material, a terminal for said conductor, an insulating sleeve for said terminal having one end embedded in said insulating material, said terminal and sleeve projecting beyond said tubular jacket, and a metallic bushing interposed between said insulating sleeve and jacket.

4. An electric heating unit comprising a metallic sheath, powdered heat refractory insulating material within said sheath, a resistance conductor embedded in said insulating material, a terminal for said conductor projecting from the sheath, and a metallic sleeve and insulator surrounding the projecting terminal and having one end secured within the sheath.

5. An electric heater comprising a metallic

jacket, a resistor mounted within said jacket and insulated therefrom, a terminal for said resistor having a part within said jacket and insulated therefrom, and a metallic bushing interposed between said jacket and said part of said terminal, said jacket being contracted to secure said bushing and said terminal therein.

6. An electric heating unit comprising a metallic jacket, a resistor mounted therein and insulated therefrom, a terminal for said resistor projecting into said jacket, insulation surrounding said terminal, a ductile metallic bushing surrounding said insulation, said jacket being contracted about said bushing for securement of the same and said terminal.

7. An electric heater comprising a metallic jacket, a resistor mounted therein and insulated therefrom, a terminal for said resistor projecting within said jacket, and a ductile metallic bushing surrounding a portion of said terminal within said jacket and insulated from said terminal, said bushing having an irregular surface, and said jacket being contracted about said bushing to interlock with said irregular surface of the latter.

In witness whereof, I have hereunto subscribed my name.

JOSEF AMON.
